PACKAGE CONTAINING ENVELOPES AND
WRITING PAPER

Elmer G. Overly, Oakmont, Pa.

Application March 31, 1945, Serial No. 585,944

8 Claims. (Cl. 206—63)

1

The present invention relates to packages containing envelopes and writing paper, and more particularly to the means by which two packs of envelopes and a pack of writing paper are arranged and held in predetermined relationship in a stationery box.

One object of the present invention is to provide a new and improved stationery package having packaging means by which two stacks of envelopes and a stack of writing paper are maintained in separate orderly stacks against relative displacement, and are protected against crushing.

Another object is to provide new and improved packing means which is adapted to hold two stacks of envelopes in a stationery box in an accessible manner to permit successive removal of the envelopes without disturbing the orderly arrangement of the stacks, which is easily folded and formed from sheet material without the use of adhesives, which contains a minimum amount of sheet material, and which is inexpensive to manufacture.

Various other objects, features and advantages of the invention will be apparent from the following particular description, and from an inspection of the accompanying drawings, in which:

Fig. 1 is a top plan view of a form of stationery package embodying the present invention, this package being shown comprising a box having a top telescoping cover which is shown removed to expose the contents of the package;

Fig. 2 is a section taken on line 2—2 of Fig. 1, but showing the package with the cover in position;

Fig. 3 is a section taken on line 3—3 of Fig. 1, but shown with the cover in position and with the envelopes and writing paper removed;

Fig. 4 is an exploded perspective view showing the folded packing inserts in separated position in accordance with the present invention, the envelope packs being shown in dot and dash lines;

Fig. 5 is a top plan view of a flat sheet blank which is creased and cut, and which may be folded to form an envelope band insert by which two packs of envelopes are held in separated orderly relationship in the box in accordance with certain features of the present invention;

Fig. 6 is a top plan view of a flat sheet blank which is creased and cut, and which may be folded to form the bridge insert between the two envelope packs in accordance with certain features of the present invention;

2

Fig. 7 shows the packing insert structure of Figs. 4, 5 and 6, but contained in a stationery box having a side closure flap;

Fig. 8 shows an exploded view of another form of stationery box insert means embodying the present invention, the envelope stacks and the writing paper stacks being shown in dot and dash lines; and

Fig. 9 is a top plan view of a flat sheet blank 10 which is creased and cut, and which may be folded to form a modified envelope band insert.

Referring to Figs. 1 to 6 of the drawings, there is shown a box 10 consisting of two telescoping sections 11 and 12. The inner box section 11 comprises bottom and side walls, and is adapted to contain therein two stacks of envelopes 13, and a stack of writing paper 14 over said envelope stacks, while the outer box section 12 forms a top closure for the inner box section 11, and has 20 a top wall and also side walls telescopically engaging the side walls of the inner box section 11.

For holding the two envelope stacks 13 in predetermined orderly position in the inner box section 11, and to protect said envelopes against 25 crushing, there is provided a packing insert 15 forming a holding band for the two envelope stacks 13, and a packing insert 16 serving as a bridge piece to separate the two envelope stacks 13, and to form a partial support for the writing paper stack 14.

The envelope band insert 15 is folded from a narrow flat elongated rectangular blank 17 (Fig. 5) of cardboard or heavy paper, which is cut and scored to define an intermediate wall section 18 extending along the bottom of the inner box section 11, and separating the two envelope stacks 13, and two band sections 19 at the opposite ends of said intermediate wall section for the respective envelope stacks. These 30 band sections 19 comprise a pair of walls 20 for the respective inner sides of the envelope stacks 13 upstanding from the ends of the intermediate section 18, and separated from said intermediate section by score lines 21, horizontal walls 22 for

40 the tops of said envelope stacks respectively separated from the upstanding side walls 20 by score lines 23, vertical walls 24 for the respective outer sides of the envelope stacks separated from the top horizontal walls 22 by score lines 25, and 45 walls 26 for the bottom of the envelope stacks separated from the outer side walls 24 by score lines 27.

To assure effective wrapping of the two envelope stacks 13 by the band sections 19 of the 50 insert 15, the blank 17 has two opposite tabs 30

cut out therefrom along the lines 31, and extending outwardly from the score lines 21. In folded condition of the blank 17, the tabs 30 extend in the plane of the intermediate stack separating section 18 of the insert and beneath the respective envelope stacks 13, and terminate at their outer ends close to the corresponding bottom walls 26 of the insert 15, so that each of said envelope stacks is almost completely encircled by the respective band section 19. This permits the insert 19 to be wrapped around the two envelope stacks 13 and the assembly to be easily transferred to the box 10 during packaging without disturbing the orderly arrangement of the envelope stacks.

The width of the insert 15 is desirably narrower than the length of the envelope, so that substantial portions of said envelopes are exposed beyond said insert. This construction affords substantial economy in the amount of sheet material employed in making the inserts 15, and at the same time, permits an envelope to be easily removed from a stack 13 without disturbing the other envelopes in said stack, or disturbing the arrangement of the other stationery units in the box 10.

The bridge piece 16 fits snugly between the two band sections 19 of the insert 15, and serves not only as a partial support for the stack of writing paper 14, but also serves to prop up said band sections against collapse. This bridge piece 16 is made from a single flat blank 35 (Fig. 6) of sheet material such as cardboard or heavy paper having longitudinal score lines 36 defining side flaps 31, and transverse score lines 38 defining end flaps 39. The corners of the blank 35 are cut out to permit said blank to be rectangularly folded downwardly along the score lines 36 and 38, to form with said flaps the sides and end walls of the bridge piece 16.

In folded set-up position shown in Figs. 1 to 4, the bridge piece 16 in the form of an inverted box will extend substantially the full length of the box 10, and of the envelope stacks 13, and across substantially the full width of the recess defined by the insert 15 between its two band sections 19, so that its flap walls 37 and 39 will be confined and retained in downwardly folded position by the corresponding walls of the inner box section 11. When seated upon the intermediate band section 18 of the insert 15, the bridge piece 16 will have its top wall substantially flush with the top walls 22 of said insert, so that this bridge piece in conjunction with the band insert sections 19 affords an effective support for the stack 14 of writing paper and effectively protects the envelopes against crushing.

The frictional engagement of the bridge piece 16 with the band insert 15 holds said insert against movement along the envelope stacks 13. This frictional hold of the bridge piece 16 on the band insert 15 is increased by the tendency of the side flaps 37 on said bridge piece to expand outwardly along the fold lines 36. Once the band insert 15 is properly centered with respect to the embraced envelope stacks 13, this insert will retain its position with respect to said stacks even during transportation, and even though the box should be supported edgewise.

The stack 14 of writing paper is substantially coextensive in area with the inside of the inner box section 11, so that it fits snugly in said box section. All of the stationery in the box 10 will therefore be neatly and orderly maintained in predetermined stacks against relative displace-

ment, and will be protected against crushing or damage ordinarily resulting from violent handling of the box during transportation.

It is possible with the packing arrangement shown to use all of the envelopes in one stack or all the writing paper without any of the remaining stationery units becoming displaced.

In Fig. 7 is shown a stationery package containing two stacks of envelopes 13, a stack of writing paper 14, and the packing inserts 15b and 16. The box 10a, instead of being of the two piece telescoping top cover type, as in the construction of Figs. 1-6, is shown of the one piece type having a closure wall 40 on one side, a closure flap 41 extending outwardly from said closure wall, and adapted to be tucked underneath the top wall of the box, and end flaps 42 adapted to be tucked behind the closure wall 40 in closed position of said wall. This box 10a can be supported in upright position shown in Fig. 7 with the closure wall 40 on top, and the envelopes and writing paper can be removed from said box while supported in this position without the necessity of slipping the entire stationery contents from the box.

The packing insert 15, Fig. 4, may be used in the construction of Fig. 7 and may be made wider relative to the length of the envelopes than in the construction of Figs. 1-6, but even if it has the same relative width, the frictional hold of the bridge piece 16 on said insert is usually sufficient to maintain said insert in substantially centered position with respect to the envelope stacks 13, even though the package is supported in upright position shown.

Fig. 8 shows a modified form of packing means which is preferably used with the type of box 10a of Fig. 7, and in which the band packing insert 15b is made from a flat blank of cardboard or heavy paper, Fig. 9, and is creased, cut and folded to form an intermediate bottom wall section 18b separating the two envelope stacks 13, and two band sections 19b at the opposite ends of said intermediate wall section for the respective envelope stacks. Each of these band sections 19b comprises walls 20b for the inner sides of the envelope stacks 13 upstanding from the ends of the intermediate sections 18b, and separated from said intermediate section by score lines 21b, and horizontal walls 22b for the tops of said envelope stacks separated from the inner side walls 20b by score lines 23b. These top horizontal walls 22b terminate at their outer ends at or near the outer edges of the envelope stacks 13.

The band sections 19b of the blank are slit along parallel lines 31b from the score lines 21b to the ends of the blank, to form tabs 30b. These tabs 30b in the flat unfolded blank project substantially to the outer ends of the top wall sections 22b of the blank, the projecting sections 46 of said tabs being separated from the main sections 47 by score lines 48. These main tab sections 47 extend in the plane of the intermediate wall section 18b of the insert 15b in folded set-up condition of said insert, to form bottom confining walls for the envelope stacks 13, and the projecting tab sections 46 are folded upwardly along the score lines 48 to form the outer side confining walls for said stacks.

The overall width of the insert 15b is shown substantially coextensive with the length of the envelopes. This has the advantage of assuring the maintenance of the insert 15b while in the box against displacement with respect to

the envelope stacks. However, as far as certain aspects of the invention are concerned, the width of the insert 15b may be smaller than the length of the envelope stacks 13 to expose the end section of said stacks beyond said insert, as in the construction of Figs. 1-7.

The bridge packing insert 16 in the construction of Fig. 8 is similar to that shown in the construction of Figs. 1-7, and is fitted as in said latter construction snugly between the two band sections 19b of the packing insert 15b.

The assembled stationery unit of Fig. 8 may be packed either in a box such as that shown in Figs. 1-6, or a box such as that shown in Fig. 7.

I have described what I believe to be the best embodiments of my invention. I do not wish, however, to be confined to the embodiments shown, but what I desire to cover by Letters Patent is set forth in the appended claims.

I claim:

1. In combination, a blank from which a packing insert for a stationery box may be formed made of a single sheet of material and having transverse score lines intermediate its ends, defining the intermediate section of the packing insert between said score lines, a pair of transverse score lines outwardly beyond said first-mentioned score lines to define with said first-mentioned score lines inner side walls for two stacks of envelopes in said box, and to define beyond said second-mentioned score lines transverse walls for one face of said envelope stacks, said blank being slit at each end of said intermediate section along a pair of transversely spaced lines extending alongside of each other outwardly from each of said first-mentioned score lines along the length of said blank, said blank having a cut joining the outer ends of the slit lines of each of said pairs of slit lines to define two tabs each spaced from the sides of the blank and extending from each of said first-mentioned score lines away from the other first-mentioned score lines and towards the adjacent end of the blank, said tabs constituting extensions of the intermediate section of the blank and adapted when said blank is folded and in use to be in the plane of said intermediate section and to engage the opposite face of said envelope stacks, and a second blank from which the bridging insert for the packing insert is formed, said second blank being constructed of a single sheet of material and having a pair of parallel score lines across its full width spaced a distance substantially equal to the distance between the first-mentioned score lines in said packing insert blank, whereby said second blank when folded fits snugly between said side walls and the section of said second blank beyond its score lines when folded form side flap walls adapted to engage said side walls.

2. A blank from which a packing insert for a stationery box may be formed, made of sheet material and having transverse score lines intermediate its ends, defining the intermediate section of the packing insert between said score lines, a pair of transverse score lines outwardly beyond said first-mentioned score lines to define with said first-mentioned score lines inner side walls for two stacks of envelopes in said box, and to define beyond said second-mentioned score lines transverse walls for one face of said envelope stacks, said blank being slit at each end of said intermediate section along a pair of transversely spaced lines extending alongside of each other outwardly from each of said first-mentioned score lines along the length of said blank,

said blank having a cut joining the outer ends of the slit lines of each of said pairs of slit lines to define two tabs, each spaced from the sides of the blank and extending from each of said first-mentioned score lines away from the other first-mentioned score line and towards the adjacent end of the blank, said tabs constituting extensions of the intermediate section of the blank and having at least portions thereof along their lengths

- 5 from said first-mentioned score lines free from transverse score lines and adapted when said blank is folded and in use to lie in the plane of said intermediate section and to engage the opposite face of said envelope stacks, the sections of
- 10 the blank beyond said second-mentioned score lines which define the transverse walls for one face of the envelope stacks being free from transverse score lines and each having a length at least as great as the length of the portion of the
- 15 adjacent tab free from transverse score lines, whereby said transverse wall defining sections in folded position of the blank will extend across the full widths of the envelope stacks and to the sides of the stationery box without interference
- 20 from said tab portions.
- 25 3. A stationery package comprising a box, two stacks of envelopes in said box, and a packing insert in said box made of a single piece of sheet material rectangularly folded to define an intermediate bottom section for spacing the two envelope stacks, and two band sections at the ends of said intermediate section for said stacks of envelopes respectively, each of said band sections defining an inner side at right angles to
- 30 said intermediate section and a top wall at right angles to said inner side and parallel to said intermediate section, said insert being slit at each end of said intermediate section along a pair of transversely spaced lines extending along-
- 35 side of each other outwardly from each end of said intermediate section along the length of said insert, said insert having a cut joining the outer ends of the slit lines of each of said pairs of slit lines to define two tabs, extending lengthwise of
- 40 said insert in opposite directions from the ends of said intermediate bottom section and in the plane of said latter section along the bottom of a respective envelope stack.
- 45 4. A stationery package as described in claim 3, comprising a bridge packing insert in said box separate from said first-mentioned packing insert and made of a single piece of sheet material rectangularly folded, said bridge insert being snugly fitted over said intermediate bottom section and between said band sections, and having side walls abutting the inner side walls of said band sections, and a top wall joining said latter side walls.

- 50 5. As an article of manufacture, a packing insert for two stacks of envelopes in a stationery box, said insert being made of a single piece of sheet material, and being rectangularly folded to define an intermediate bottom section for spacing the two envelope stacks, and two band sections at the ends of said intermediate section for said
- 55 stacks of envelopes respectively, each defining inner side walls at right angles to the intermediate bottom section and top walls, said band sections being slit at each end of said intermediate section along a pair of transversely spaced lines extending alongside of each other outwardly from each end of said intermediate section along the length of said insert, said insert having a cut joining the outer ends of the slit lines of each
- 60 of said pairs of slit lines to form two tabs ex-
- 65
- 70
- 75

tending lengthwise of said insert in opposite directions from the ends of said intermediate bottom section and in the plane of said latter section.

6. A packing insert as described in claim 5, each tab terminating at its outer end short of the end of the corresponding band section and constituting a cut-out of the corresponding inner side and top wall of said latter band section, said latter inner side and top wall having an opening resulting from said cut-out extending from the adjoining end of the intermediate section and terminating in said latter top wall short of the outer end thereof.

7. A packing insert as described in claim 5, in which said band sections are rectangularly folded to define in series inner side, top, outer side and bottom walls, said bottom walls being at the ends of said band sections.

8. A packing insert as described in claim 5, in which said tabs have a length which is substantially coextensive with the length of said band sections, whereby said tabs extend across substantially the full width of the envelope stacks.
